UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

INDUCTANCE SYSTEM

Application filed November 12, 1929. Serial No. 408,708.

My invention relates broadly to high power radio transmission apparatus and more particularly to an inductance change system for high frequency signaling circuits.

5 One of the objects of my invention is to provide a construction of inductance change system for high power, short wave radio transmitters in which losses may be maintained at a minimum by the circulation of 10 cooling fluid through the active inductance in the transmitting circuit.

Another object of my invention is to provide an inductance change system for radio transmitters in which inductances of different 15 effective values may be electrically connected in the transmission circuit and a cooling fluid supplied to the individual inductances for maintaining the operation of the transmitting circuits under conditions of 20 minimum loss.

A further object of my invention is to provide a construction of inductance change system in which a multiplicity of inductances, each having different values, may be individually and selectively connected in the transmitter for operation of the transmitter at predetermined frequency and a cooling fluid supplied through the inductance which is in 25 use for the operation of the transmitter circuit at maximum efficiency.

Other and further objects of my invention reside in the construction of inductance change system for high frequency, high power transmitters and the means for circulating a cooling fluid through a selected inductance in the transmitter system as set forth more fully in the specification herein-after following by reference to the accompanying drawings, wherein:

40 Figure 1 is a plan view of the inductance change system showing one of the inductances coupled for the supply of cooling fluid thereto; Fig. 2 is a cross-sectional view on line 2-2 of Fig. 1 showing the arrangement of 45 the inductance units which are available for connection in the transmitter circuit and the arrangement of a selected inductance connected in the transmitter circuit in position for receiving cooling fluid which passes 50 through the inductance; Fig. 3 shows the in-

ductance system rocked to a position where the cooling fluid connection can be disconnected preparatory to the shift of frequency of the transmitter; Fig. 4 is a cross-sectional view on line 4-4 of Fig. 1, illustrating the 55 control means for the valves by which the passage of fluid from the fluid cooled high power tube system to the individual inductance units may be controlled; Fig. 5 is a fragmentary cross-sectional view illustrating the control valves, illustrated in Fig. 4, moved to an extreme opposite position in which the inductance is unlocked with respect to the feeder pipes leading from the high power 60 fluid cooled tube system; Fig. 6 is a cross-sectional view taken through the feeder pipe and one end of the inductance, and showing the feeder pipe and inductance aligned for the 65 passage of cooling fluid; Fig. 7 is a cross-sectional view taken through the feeder pipe 70 and inductance terminus of Fig. 6, but illustrating the pipes separated and about to be connected; Fig. 8 is an end elevation on line 8-8 of Fig. 7; Fig. 9 is a cross-sectional view on line 9-9 of Fig. 7; Fig. 10 is an end view 75 of the terminus of the inductance looking in the direction of line 10-10 of Fig. 7; and Fig. 11 is a side elevation of the terminus of 80 the inductance.

In high power radio transmitters covering 85 a wide frequency band the output inductance must be changed for operating the transmitter on different frequencies in the band. In high power operations it is also necessary to use fluid cooled tubes, the cooling fluid of 90 which is supplied normally through an insulating tubing wound on a frame and connected at one side to the liquid supply and at the other side to the liquid jacket in which the tubes are placed. This arrangement, 95 however, involves a certain amount of loss due to the action of the radio frequency energy near the point where the insulating tubing is connected to the liquid jacket. This loss may be in the insulating material of which the tube is made or in the cooling liquid itself or both.

In the development of high frequency transmitters, I have found that a considerable increase in efficiency may be obtained by 100

cooling the output inductances in the transmission circuit and eliminating the cooling coil heretofore utilized for the cooling fluid which passes around the anodes of the high power tubes. I provide means for cooling the output inductances by the same fluid which is conveyed around the anodes of the high power tubes. This arrangement eliminates unnecessary leads from the high power tubes, and extremely short connections may be made by the direct connection of the inductance unit with the fluid feeder pipes which connect to the cooling jackets of the high power tube. I provide means for closing the fluid feeder pipes from the high power tube system when it becomes necessary to change the effective inductance in the transmitter circuits. Each inductance has the end thereof equipped with a valve and as the inductances are changed the valves are closed to prevent leakage of fluid during the interchange of one inductance coil for an inductance coil of different value. The equipment which I employ for locking an inductance in the fluid cooling circuit may be actuated rapidly for the removal of one inductance from the transmitter circuit and the substitution of an inductance of different frequency in the transmitting circuit. A complete change in frequency may be effected with minimum delay and the operation of the transmitter circuit at maximum efficiency is insured by virtue of short interconnecting leads and the control of the temperature of both the inductance and the high power tubes which are operated in the transmitter system.

Referring to the drawings in detail, reference characters 1 and 2 designate the fluid cooled tube systems which may be associated with the condenser system 3. An insulating frame 4 is provided adjacent the fluid cooled tube systems 1 and 2, the frame being angularly movable about an axis within limits defined by pins 6 and 7. Insulating frame 4 consists of a pair of arms between which there is journaled a shaft 8 which projects through a front panel 9 of the transmitter with a control knob 10 thereon by which shaft 8 may be rotated. The shaft 8 carries an insulating frame structure constituted by end members 11 and 12 between which insulating supports or arms 13, 14, 15 and 16 extend. Inductances of differing values are supported on the respective arms, that is the largest inductance coil 17 is shown mounted on insulating arm 13; a smaller inductance 18 is mounted on arm 14; a smaller inductance 19 is located on arm 15 and a still smaller inductance 20 is carried by arm 16. The inductances are formed in twin conductor metallic tubing secured together by any suitable method such as brazing or soldering. These two tubes provided an inlet and an outlet circuit for the cooling fluid supply as well as a path for the electrical circuits through

the inductance and through the transmitter. Near the center of each coil the two tubes forming the twin conductor of the coil are spread to enable fluid connections to be made with the coil. For example, inductance 17 has the adjacent center turns connected through inlet and outlet pipes 21 and 22 with the end of the coil terminating in inlet and outlet pipes 23 and 24 at one end, and 25 and 26 at the opposite end. Similarly, inductance 18 has its ends provided with inlet and outlet pipe connections at 27 and 28 at one end, and 29 and 30 at the opposite end. At the center of the coil, inlet and outlet connections are provided as represented at 31 and 32. In a similar manner inductance 19 has inlet and outlet pipe connections 33 and 34 at one end, and 35 and 36 at the opposite end, with pipe connections 37 and 38 adjacent the center of the inductance. The fluid connections to the cooling jackets of electron tubes 1 and 2 and to the centers of the coils, terminate at 31—32, 39—40 and 41—42. Each of the terminal pipes is provided with a coupling head 43 which has been illustrated more clearly in Figs. 6—8. Each of the coupling heads 43 are angularly movable by means of lever arms 44 which are shiftable by means of a plunger rod 45, of insulating material, horizontally movable from the front of the panel mounting through slot 46 by means of knob 47. The coupling head 43 is maintained in position on the end of each of the pipes 37—42, inclusive, by means of bushing 48 which may be fixed adjacent the terminus of each pipe.

The construction of the terminus of the pipes 31, 32, 40, 41 and 42 may be understood more clearly by reference to Figs. 6—9. The terminus of each pipe 31 is provided with a flange 50 which provides an abutment for the end of the coupling head 43. The coupling member 51 is internally screw threaded as represented at 52 to engage the external screw threads 53 on the coupling head 43 in such manner that the coupling member 51 is free to be shifted angularly with the movement of coupling head 43. The coupling member 51 is provided with inwardly directed projections 54 which are alternately positioned around the inner periphery of the coupling member 51 and are spaced to provide gaps 55 which conform with the projections 56 integrally formed on the end of the tubular inductance as represented at 28. The ends of the tubular inductances and the fluid inlet and discharge pipes are each provided with a valve mechanism normally maintaining the fluid passages closed preparatory for automatic opening when the ends of the inductance are brought into registering relation with the fluid inlet and discharge terminal pipes. I have shown the arrangement of valve mechanism in the aligned passages in Figs. 6 and 7. The terminus of pipe 31 is

provided with a spider 57 positioned internally of the pipe 81 adjacent the end thereof, the spider being apertured at 58 for the passage of fluid and having a pin 59 supported 5 therein and arranged to maintain a spring 60 in central position, which spring acts against ball valve 61 tending to move the ball valve toward the seat 62 of sleeve member 63 which is screw threaded to engage the internal screw 10 threads on the end of the terminus 81. The sleeve 63 is provided with a spider 64 which supports the slid able member 65. The slid able member 65 has a head 66 which may be engaged by the head 67 which is mounted in 15 the end of the fluid passage 28 of the inductance unit. The head 67 is carried by a stem 68 slid able in spider 69 which is supported on sleeve 70 which carries valve seat 71. The ball valve 72 is normally wedged against valve 20 seat 71 or spring member 73 which is supported on central pin 74 mounted on spider 75. The spider 75 is suitably apertured for the passage of fluid as indicated at 76. The normal position of the ball valves 61 and 72 25 has been shown in Fig. 7 when the fluid pipes of the inductance unit are about to be aligned with the fluid terminus pipes which are positioned adjacent the movable frame 11. In this position the ball valves 61 and 72 are 30 seated upon the seats 62 and 71 respectively and the fluid passage from the inductance and fluid terminus positioned adjacent the inductance thereby closed. When the coupling member 51 is rotated by moving horizontal 35 bar 45 which communicates motion through coupling head 43, a position may be reached at which the projections 56 on pipe 28 may pass between the inwardly directed projections 54 on coupling member 51 enabling the 40 heads 67 and 66 to abut one with respect to another. Continued movement of the shift able frame 4 toward the stationary terminus pipes introduce pressure between the heads 66 and 67 forcing the ball valves 61 and 72 45 from their seats against the pressure of springs 60 and 73 and completing the passage for the flow of cooling fluid from the terminus pipe 37 through the tube 28 of the inductance unit. The head 66 is apertured at 50 66a and head 67 has aligned apertures at 67a thus forming no obstructions to the passage of fluid. The pins 65 and 66 are limited in their movement by stops 65b and 68b. A gasket 77 fits into an aligned annular recess 55 78 in sleeve 70 thereby insuring a water tight joint between the inductance and the fluid supply terminus.

The operating mechanism is shown more clearly in Figs. 4 and 5 where Figure 4 indicates the inductance unit locked in position with respect to the stationary fluid supply and discharge pipes, and Figure 5 illustrates the control bar 45 moved to a position where the inductance unit is about to be connected 60 to the fluid supply or discharge pipes, or in

position where the inductance units are about to be disconnected and removed from the stationary fluid discharge and supply pipes. The locking bar 45 is notched at 45a and 45b to enable the bar to be maintained in a predetermined setting by the latching of the bar over the edge 46a of slot 46. The levers 44 which project from the coupling heads 43 connect to the bar 45 by means of links 45c, and 45d, by which the entire group of coupling heads may be moved simultaneously to a selected position.

I provide locking means 80 on the frame 11 in the form of detents which slide into notches formed in the frame 4 to maintain an inductance unit in a particular position when frame 11 has been moved to such position.

It will be observed that connections may be established for the conduction of fluid through a selected inductance unit at the same time that the inductance unit is electrically connected in circuit with the associated parts of the radio transmitter. The shifting of the transmitter from one frequency to another frequency may be rapidly accomplished and high efficiency in the transmitter maintained.

While I have described my invention in certain preferred embodiments I desire that it be understood that modifications may be made and that no limitations upon my invention are intended other than are imposed by the scope of the appended claims.

What I claim as new and desire to secure by Letters Patent of the United States is as follows:

1. In a variable inductance system, a rotatable frame, a plurality of inductance units of different inductance values carried by said rotatable frame, each of said inductance units being constituted by fluid conducting tubes, fluid connections for the ends of said tubes terminating adjacent said frame, and means for shifting said frame into position for establishing connection between the ends of said inductance units and the fluid supply terminals adjacent said frame.

2. An inductance system comprising a rotatable frame, a plurality of inductance units carried by said frame, each of said inductance units comprising a tubular conductive member having terminal connections at opposite ends thereof, fluid circulation terminals fixed adjacent said frame, and means for connecting the ends of a selected one of said inductance units with said fluid circulation terminals for the passage of a cooling fluid through a selected inductance unit.

3. An inductance system comprising a frame structure of insulating material, inductance units of different values carried by said frame structure, each of said inductance units comprising a fluid circulating conductive tubing having inlet and outlet terminals connected thereto, fluid circulation pipes fixed

- adjacent said frame, and means for establishing connection between the inlet and outlet terminals of a selected one of said inductance units with said fluid circulation pipes for the passage of cooling fluid through selected ones of said inductance units.
4. In an inductance system, a rotatable frame of insulating material, means for mounting said frame for rockable movement with respect to an adjacent support, a multiplicity of inductance units carried by said frame structure, each of said inductance units being constituted by a hollow conductive tubing having inlet and outlet connections at opposite ends thereof, fluid supply terminals carried by said adjacent support, and means for establishing connection between said fluid supply terminals and the ends of a selected one of said inductance units for the passage of a cooling fluid through a selected inductance unit.
5. An inductance system comprising a rotatable frame structure of insulating material, inductance units carried on the periphery of said frame structure, each of said inductance units being constituted by a fluid circulating tubing having terminals for the supply and discharge of cooling fluid, a set of fixed fluid supply and discharge terminals positioned adjacent said frame structure, said frame structure being rockable to move the terminals of a selected inductance unit into alignment with said fixed fluid supply and discharge terminals for the circulation of a cooling fluid through a selected inductance unit.
6. An inductance system comprising a rotatable frame structure of insulating material, inductance units of different values carried by the periphery of said rotatable frame structure, each of said inductance units being constituted by a conductive tubing having inlet and discharge fluid passages connected thereto, fluid delivery and discharge terminals positioned adjacent said rotatable frame structure, said rotatable frame structure being angularly movable for aligning the fluid passages of a selected inductance unit with said fluid delivery and discharge terminals, and means for coupling said terminals and fluid passages for the circulation of fluid through a selected inductance unit.
7. An inductance system comprising a frame structure of insulating material mounted for rotative movement on a central shaft, a multiplicity of inductances of differing values supported upon the periphery of said rotatable frame structure, each of said inductances being constituted by conductive tubes having inlet and delivery passages, a set of fixed fluid inlet and discharge terminals mounted adjacent said frame structure, said central shaft being angularly movable within predetermined limits for aligning the fluid inlet and delivery passages on a selected inductance unit with the fixed fluid inlet and

discharge terminals, and coupling means operative to maintain said fluid passages in fluid tight relation to said inductance units.

8. An inductance system comprising a frame, a rotatable shaft journaled in said frame, a rotary frame carried by said rotatable shaft, a multiplicity of inductances of different electrical values supported on the periphery of said frame, said inductances each comprising a conductive tubing having fluid inlet and discharge passages therein, a set of fixed fluid delivery and outlet terminals positioned adjacent said frame and aligned with the inlet and discharge passages on said inductances, means for shifting said frame for moving the inlet and discharge passages on said inductances into or out of engagement with said fixed fluid and outlet terminals, and coupling means operable to maintain said fixed terminals in connection with the passages on a selected inductance for the circulation of cooling fluid therethrough.

9. An inductance system comprising a frame, a rotatable shaft journaled in said frame, a rotary frame carried by said rotatable shaft, a multiplicity of inductances of different electrical values supported on the periphery of said frame, said inductances each comprising a conductive tubing having fluid inlet and discharge passages thereon, a valve in each of said passages, a set of fixed fluid delivery and discharge terminals positioned adjacent said frame, a valve in each of said terminals, means for shifting said frame toward said fixed fluid delivery and discharge terminals for actuating the valves in said passages and in a selected inductance, and means for locking a selected inductance with respect to said fluid delivery and discharge terminals for the passage of a cooling fluid therethrough.

10. In an inductance system, a frame structure, a multiplicity of inductances carried by said frame structure, each of said inductances being constituted by a conductive tubing having inlet and discharge fluid passages therein, a set of fixed fluid delivery and discharge terminals mounted adjacent said frame structure, said frame structure being movable to align the passages on a selected inductance with said terminals, and valves carried in said terminals and in the passages in said inductances for normally closing said terminals and passages, said valves operating to open a fluid path through said terminals and inductances when said passages are coupled with said terminals for providing a circulatory path for cooling fluid through a selected inductance unit.

LOUIS A. GEBHARD.
